UNITED STATES PATENT OFFICE

2,240,277

SAFETY APPARATUS

Orren E. Zoder, St. Louis, Mo., assignor, by mesne assignments, to Zoder, Incorporated, St. Louis, Mo., a corporation of Missouri

Application November 18, 1939, Serial No. 305,159

10 Claims. (Cl. 137—68)

This invention relates to safety apparatus, and with regard to certain more specific features, to safety apparatus for tanks which carry dangerous fluids, such as inflammables or the like.

The invention is an improvement upon the invention disclosed in my United States patent application, Serial No. 214,735, filed June 20, 1938, for Safety apparatus and now Patent No. 2,194,348 granted March 19, 1940, of which the present invention is in part a continuation.

Among the several objects of the invention may be noted the provision of means for cutting off dangerous liquid under emergency conditions, wherein failure of operation under any non-emergency conditions may quickly be rectified; the provision of apparatus of the class described in which part of the said emergency cut-off means is used for indicating an uncapped condition of a tank; the provision of apparatus of the class described which includes highly sensitive means which under normal operating conditions prevents escape of products of evaporation, but which under abnormal conditions permits their free escape to reduce pressure; the provision of apparatus of the class described which without much change in the basic mechanical form may be constructed (when desired) so as to release said products of evaporation under normal operating conditions; and the provision of a simple form of safety apparatus adapted to avoid an emptying siphoning action on tanks under abnormal conditions. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are shown several of various possible embodiments of the invention,

Fig. 1 is a vertical section of a fuel tank, parts being in elevation, showing one form of the invention;

Fig. 2 is a fragmentary plan view of Fig. 1;

Fig. 3 is a horizontal section taken on line 3—3 of Figs. 1 and 4, which, with respect to Fig. 1, is enlarged;

Fig. 4 is an enlarged vertical section taken on line 4—4 of Fig. 2;

Fig. 5 is an enlarged vertical section which is at a right angle to Fig. 4 and which is taken on line 5—5 of Fig. 2;

Figs. 6, 7 and 8 are horizontal sections taken

on lines 6—6, 7—7 and 8—8, respectively, of Fig. 4;

Fig. 9 is a fragmentary vertical section showing a fusible plug;

Fig. 10 is a fragmentary vertical section of an alternative form of the invention; and,

Fig. 11 is another fragmentary vertical section on a part of the Fig. 10 embodiment.

Similar reference characters indicate corresponding parts throughout the several views of the drawings.

Referring now more particularly to Fig. 1, there is shown at numeral 1 a gasoline tank, which is an example of the class of apparatus to which the present invention applies. This tank has an opening 3 (Fig. 4) within which is fastened by brazing, welding, or the like 5, a flanged member 7. This member 7 has a skirt 9 which extends into the tank 1 for the purpose of limiting the height to which the liquid level 11 may be raised in the tank. That is, after the fluid level 11 reaches the maximum elevation on the bottom of the skirt 9, air is trapped within the tank above and outside the skirt to prevent further rise in said level. However, the level may then rise within the skirt to effect an overflow (or potential overflow) condition in order to warn the operator that filling has been completed to the greatest extent possible.

Threaded into the flange 7 is a downwardly projecting body 13 which is sealed to the flange member 7 by means of a gasket 15. This body 13 is hollow and consists essentially of a top portion 17 in which is an opening 19 closed by a cover 21. A gasket 23 is located in a groove in the bottom of the cover 21. The cover includes a threaded pin 25 which has a loose rotary connection at 27 with a winged cap 29, the latter being removably threaded into an opening 31 above the opening 19. The gasket 23 is adapted to seat upon an edge 33 arranged between the threaded opening 31 and the opening 19. The winged cap 29 is rotary with respect to the pin 25 and has a slight angular play with respect thereto, so that, upon applying the assembly of the winged cap 29 and cover 21 and by screwing the winged cap 29 into the opening 31, the gasket 23 may squeeze against its seat after contact without rotary motion, thus preventing scarification of the gasket 23 and assuring a permanently good seal.

The mid, closed-in portion 49 of the body 13 is connected with the top portion 17 by means of four pillars 35, 37, 39 and 41, around which, in recesses 43, are located concentric screens 45,

the inner one of which screens is relatively coarse, and the outer one of which is relatively fine. The coarse screen protects the fine screen from being dented and the fine screen serves as a strainer.

Thus, the pillars 35, 37, 39, 41 form a laterally open space 47 through which gasoline may flow out around the pillars and through the screens 45 to a point within the skirt 9 from whence it is deflected to gravitate into the tank 1. The skirt 9 thus serves both as a deflector and an air trap.

In order that the nozzle of the gasoline filling hose may not be blocked by resting flat upon the intermediate floor member 49 of the space 47, there is formed in said floor 49 a ridge 51 which serves as a support for the end of the nozzle, but which is narrow enough that it will not close off the nozzle. Thus, under any conditions of nozzle insertion there is insured a free flow of gasoline from the nozzle and through the chamber 47. Furthermore, the ridge 51 has its side curved as at 53, to assure a fairly streamlined motion of the liquid laterally to the screens 45.

Below the floor 49 is a substantially enclosed float-chamber compartment 55 which has a bottom 57 and cylindric sides. In the bottom 57 is a depression 59 for seating a ball weight 61. Slightly spaced above the latter is a hollow float 63 mounted upon a lever 65. The lever 65 is pivoted at 67 to ears 69 of a support 71. The support 71 includes a downwardly extending stop 73 for engaging a corresponding stop 75 on the end of the lever 65. Thus, the downward motion of the lever (and of the float 63) is limited to a place just above the ball 61.

The support 71 is held between sealing gaskets 77 by means of a threaded valve casing 79. The casing is threaded into a boss 81, extending 40 downwardly from the intermediate wall 49.

In the valve casing 79 is a cylindric hollow portion which slidably carries a polygonal valve pin 83, the latter normally resting upon the lever 65 and having a seat 85 which is cooperable with a valve seat 87 in the top of the valve casing 79. The opening within the seat 87 communicates with a passage 89 which in turn leads to a vertical passage 91 through the pillar 41. The passage 91 leads upwardly to an inlet 93 and communicates with the atmosphere.

When the lever 65 has its stop 75 against the stop 73, and the float 63 gravitates down, as indicated in Fig. 4, then the valve 83 is opened, thus permitting air to enter and leave the lower 55 space 55.

If the apparatus tilts a substantial amount, as in an overturning accident, then the ball weight 61 automatically moves against the weight 63 to close said valve 83. Thus, if the tank 1 overturns in an accident, gasoline cannot escape to a dangerous exterior point through the vent 91. The lever 65 provides a mechanical advantage between the float 63 and valve 85.

As indicated in Fig. 5, the compartment 55 is in communication with a point near the bottom of the tank by means of a passage 95 and a pipe 97. Whenever gasoline enters the tank, as above described, its level may rise in the pipe 97 at passage 95 (with its level in the tank), because 70 of the free exit of air permitted by the open valve 85 from the connected space 55.

At about the time that the liquid level 11 rises, both within and without the compartment 55, to the maximum lower edge portion of skirt 9 (see 75

Fig. 4), the float 63 is raised and the valve 85 closed. Thus, all connection between the interior of the tank and the atmospheric exterior is cut off. By this means, the octane rating of the 5 gasoline, for example, is preserved by preventing evaporation to the atmosphere. Under warm conditions, such as on a warm day, evaporation may take place into the space above the level 11 and outside of the skirt 9, thus placing a moderate superatmospheric pressure upon the contained gasoline. This may occur at any liquid level, such as for example under conditions of a half-full tank, and under such conditions it is still desirable to prevent evaporation losses. The 15 present construction prevents such loss by reason of the fact that the superatmospheric pressure (due to evaporation) exerted upon the liquid level of the gasoline in the tank forces the gasoline up the pipe 97 and through the passage 95 to the compartment 55, thus raising the liquid level in the latter to a point where the float 63 is maintained in a raised position to close the valve 85. Thus, pressure engendered by evaporation serves to cut off escape of evaporating fluid. Of course, when evaporation does not occur, as on a cold day, there may be no inside pressure to cause raising of the liquid level around the float 63 in compartment 55, but under such conditions an open valve 85 does not result in any substantial evaporative loss, because there is substantially no evaporated fluid.

In order to withdraw gasoline from the tank under normal conditions, there is provided the suction line 99 leading to the usual gasoline pump or the like. This is connected with the passage 101 which passes downwardly through the pillar 37 to a point beneath the bottom 57. Attached beneath the bottom 57 is a cap 103 which holds in place a stainless steel flexible diaphragm 105 which permits no leakage therethrough and which is provided at its central portion with a hermetically sealed anvil 107.

The passage 101 communicates to a point beneath the diaphragm 105 by means of a passage 109, and reduced pressure caused by suction in the line 99 will depress the flexible diaphragm 105. The anvil 107 of the diaphragm 105 operates to open a valve 111 which is normally biased upward to close by means of a spring 113. The passage 115 beneath the valve 111 is provided with a strainer 117 and communicates with a pipe 119 which leads to a point near the bottom of the tank 1. Atmospheric pressure is admitted above the diaphragm 105 by means of a branch passage 121 leading from the passage 91.

Thus, when suction occurs in the line 99, the reduced pressure under the diaphragm causes diaphragm depression and opening of the valve 111 against action of spring 113. Liquid then passes from the pipe 119, through the valve 111 and through passages 109 and 101 to said line 99. Whenever suction ceases in the line 99, pressure builds up beneath the diaphragm 105 and the spring 113 recloses the valve 111. The result is that, if the suction line 99 should break while the tank is overturned, no liquid would flow therefrom in view of the closed valve 111.

Passage 101 has a branch indicated at 123 which leads to the seat 33. The end of the branch 123 is closed off by the gasket 23 when the cover 21 is held in place. Whenever said cover 21 is removed or is loose, then the by-passage 123 is opened. This breaks the suction in the port 101 and prevents the diaphragm 105 from depressing the valve 111. Thus, if the operator attempts to leave a filling point with the

cover 21 removed, he cannot do so to any great distance, because when he starts the engine, he has no substantial amount of gasoline available. He may be able to start the engine on the gasoline that is available in the carburetor, but this is soon exhausted, and he is led soon to discover his mistake of having forgotten replacement of the cover 21. Thus, the device functions as a tell-tale requiring application of the tank cover before proceeding far from a filling point.

Another feature is that, if the diaphragm 105 should accidentally break, due to wear, no gasoline can be withdrawn over the line 99 as connected in Fig. 4, because air which is available above the diaphragm by way of passages 91 and 121 passes through the leaking diaphragm 105, and to a point therebeneath to balance pressure and close valve 111, thus preventing suction of gasoline. Thus, the operator is warned of a difficulty and to permit him to proceed until repairs can be made the construction of Fig. 5 is used. An auxiliary passage 125 passes downwardly through the pillar 35, past the compartment 55 and through the head 103, where it is provided with a suction pipe 127 which reaches within a short distance of the bottom of the tank. This passage 125 is normally sealed off by means of a threaded plug 129 over which is placed a removable substance such as tell-tale, red sealing wax 131. Thus, in the case of a leak of air through the diaphragm 105, he is warned by cessation of engine operation. He then simply disconnects the suction line 99 (Fig. 4) and reconnects said line 99 to the passage 125 (Fig. 5), after having removed the plug 129. By this means, with suction in the line 99, gasoline is extracted directly from the bottom of the tank in the usual way. Under these emergency conditions, the safety features of the present apparatus due to the diaphragm 105 are temporarily of no benefit. But the operator, when he receives no gasoline over the line 99, needs not to carry out any substantial repair work, but simply reconnects the line 99. This is a simple operation.

In Fig. 9 is shown the provision of an emergency port 131 which at the upper end carries a screen 133 covered by means of a fusible material 135 such as a lead alloy which will melt at a temperature of about 170° F. The purpose of this is to provide a fusible releasing element which under high temperatures will vent the tank substantially. It is clear that it is advantageous that the vent 91 be small. On the other hand, such a small vent connection is ordinarily not enough to vent products which are evaporated at a high rate, such as under conditions of fire burning around the tank in case of an accident. When such a fire occurs, the fusible plug 135 will melt out and permit the venting at the desired rate because of the increase in size of the emergency outlet 131. It is of course true that the vented material is inflammable, but it is always more desirable to permit such material to burn in the case of an accident than to have the pressure in the tank build up and cause the tank to explode and thus throw its flaming material to substantial distances. The screen 133 is of a fine enough mesh to act as a Davey screen to prevent flame propagation into the tank through the opening 131.

In Figs. 10 and 11 is shown an alternative feature not incorporated in the structure thus far described. This is in the provision of a small cross vent 137 near the top of the skirt 9 connecting its interior with its exterior. There is

also provided an opposite passage 139 in the member 13 which communicates through passages 141 with the lower compartment 55. As shown in Fig. 11, the pipe 97 is not used in connection with passage 95, the latter being plugged as shown at 124. The purpose of this alternative construction is to fulfill the needs of those who desire a permanent communication between the interior of the tank and the exterior through a vent. With this construction the operation upon filling is for the rising liquid level to force out air over the ports 139 and 141, through the compartment 55 and through the open valve 83. When the liquid level reaches the skirt, it ceases to rise outside of the skirt at any substantial rate, because of the smallness of the size of the port 137 for relieving trapped air above level 11. Thereafter it quickly rises within the skirt, because of the small open connection with the atmosphere through port 19, until it overflows. It ordinarily never reaches the opening 139 because when the tank overflows at the inlet the operator ceases filling. If it does reach to the opening 139, the interval is so short as to be inconsequential from the viewpoint of movement of liquid into the chamber 55. Thereafter the liquid level within the skirt falls to the level around the bottom of the skirt 9, because of the gradual equalizing effect of the port 137. Then the tank normally operates with a communication 137, 139, 141, chamber 55, open valve 83, and port 91 to the atmosphere. Pressure due to evaporation is lost through these ports.

It is clear that, when the alternative is used as shown in Figs. 10 and 11, the float 63 no longer has the function of closing the valve 85 in response to a rising liquid level, because there is then no rising level in the compartment 55. Float 63 then serves only the function of receiving the weight of the ball weight 61 upon turnover of the tank, in order to avoid loss of fluid which might be forced out over the passage 139, 141 and to the compartment 55.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. Filling apparatus for liquid tanks and the like comprising a member having an upper inlet with sides, a deflecting member beneath said inlet, pillars connecting the deflecting member with the sides of the inlet, ridge means forming a part of the deflecting member and directed upwardly to form a rest for any inserted liquid-delivering nozzle, said ridge portion being streamlined from its upper edge and in downward and lateral directions, and a downwardly directed skirt surrounding said inlet member and spaced from said pillars.
2. In apparatus of the class described, a fuel tank, a member in the tank having an enclosed float chamber, a connection from said chamber to a point near the bottom of the tank, a depending skirt surrounding said member and adapted to limit the liquid level in the tank to a point below the top of the tank to trap air, a vent connecting the outside of the tank with said float chamber, a gravity-opened valve in said vent, a float in said float chamber adapted to operate said valve to close upon the liquid level in said

float chamber reaching a predetermined elevation, said connection between the float chamber and the point near the bottom being adapted to cause a liquid level in the float chamber to be high enough in the float chamber under vapor pressure above the liquid in the tank so as to close said valve independently of the position of the liquid level in the tank.

3. In apparatus of the class described, a fuel tank, a member in the tank providing an enclosed float chamber, an open connection from said chamber to a point near the bottom of the tank, a vent connecting the outside of the tank with said float chamber, a gravity-opened valve in said vent, a float in said chamber adapted to operate said valve to close when the liquid level in said tank reaches a predetermined elevation.

4. In apparatus of the class described, a fuel tank, a member in the tank providing an enclosed float chamber, an open connection from said chamber to a point near the bottom of the tank, a vent connecting the outside of the tank with said float chamber, a gravity-opened valve in said vent, a float in said chamber adapted to operate said valve to close when the liquid level in said tank reaches a predetermined elevation, said connection being adapted normally to conduct air to the tank from the float chamber, and to conduct fuel from the tank to the float chamber under pressure due to fuel evaporation in the tank.

5. In apparatus of the class described, a fuel tank, a member in the tank providing an enclosed float chamber, an open connection from said chamber to a point near the bottom of the tank, a skirt surrounding said member and depending into the tank and adapted to limit the liquid level therein to a point below the top of the tank to trap air, a vent connecting the outside of the tank with said float chamber, a gravity-opened valve in said vent, a float in said chamber adapted to operate said valve to close when the liquid level in said tank reaches said skirt, said connection being adapted normally to conduct air to the tank from the float chamber, and to conduct fuel from the tank to the float chamber under pressure due to fuel evaporation in the tank.

6. In apparatus of the class described, a fuel tank, a normally sealed suction line leading into said tank, said tank having a portion providing a filling opening, a cap for said opening, and means communicating between said suction line and said opening portion which is normally closed by said cap, the absence of the cap unsealing said suction line and its application sealing the same to permit suction therein.

7. In apparatus of the class described, a fuel

tank, a member attached to said tank and providing a filling opening, a skirt extending downwardly into said tank and spacedly surrounding said member to a point below the opening, said skirt determining a volume outside the skirt for trapping air within the tank, a relatively small passage through the skirt connecting the trapped air with the volume within the skirt, and vent means connecting said volume within the skirt with the exterior of the tank.

8. In apparatus of the class described, a fuel tank, a member attached to said tank and providing a filling opening, a skirt extending downwardly into said tank and spacedly surrounding said member to a point below the opening, said skirt determining a volume around it within the tank for trapping air upon filling the tank, a passage through the skirt connecting the trapped air with the volume within the skirt, vent means connecting said volume within the skirt with the exterior of the tank, and a valve in said vent means adapted automatically to close upon substantial angling of the tank.

9. In apparatus of the class described, a fuel tank, a member attached to said tank and providing a filling opening, a skirt extending downwardly into said tank and spacedly surrounding said member to a point below the opening, said skirt determining a volume for trapping air outside the skirt but within the tank upon filling the tank, a small restrictive passage through the skirt connecting the trapped air with the volume within the skirt, vent means connecting said volume within the skirt with the exterior of the tank, and a valve in said vent means adapted automatically to close upon substantial angling of the tank.

10. In apparatus of the class described, a fuel tank, a member in the tank providing an enclosed float chamber, an open connection from said chamber to a point near the bottom of the tank, a restricted vent connecting the outside of the tank with said float chamber, a normally open valve in said vent, float means in said chamber adapted to operate said valve to close when the liquid level in said tank reaches a predetermined elevation, said connection being adapted normally to conduct air to the tank from said restricted vent according to the requirements of reduced pressure within the tank, and to conduct fuel from the tank to the float chamber under conditions of excess pressure in the tank caused by fuel evaporation, auxiliary and relatively unrestricted outlet means from the tank to the atmosphere, and a fusible plug in said last-named outlet means.

ORREN E. ZODER.
